UNITED STATES PATENT OFFICE.

GEORGE C. HARLIN, OF SEATTLE, WASHINGTON.

CAR-COUPLING.

SPECIFICATION forming part of Letters Patent No. 730,910, dated June 16, 1903.

Application filed September 25, 1902. Serial No. 124,875. (No model.)

To all whom it may concern:

Be it known that I, GEORGE C. HARLIN, a citizen of the United States of America, residing at Seattle, in the county of King and State 5 of Washington, have invented certain new and useful Improvements in Car-Couplers, of which the following is a specification.

This invention relates to car-couplers, and particularly to those known as the "Master 10 Car-Builders' coupler" now in general use.

The object of the invention is to produce a coupler having a latch coacting with a shoulder of the draw-head, whereby the knuckle is locked in engagement with the knuckle of the 15 opposite head and whereby the said knuckle is prevented from turning on its pivot except when the latch is disengaged.

Furthermore, the object resides in the provision of a locking connection between the upper 20 wall of the coupler-head and the knuckle, whereby the action of the latch serves to wedge the knuckle into engagement with the locking means, thereby affording another means for holding the knuckle in the draw-head.

Furthermore, the object of the invention is 25 to produce means whereby the latch may be disengaged from its shoulder and held disengaged until the cars are drawn apart and uncoupled.

Furthermore, the object of the invention is 30 to produce a guide over which the latch is swung during the movement of the knuckle, and it is the purpose of the invention to hold said latch on an approximately horizontal

35 plane in order that a minimum amount of wear will result. A web or flange is provided in the horn or guide-iron of the coupler-head to act as a support for the latch when the knuckle has been swung to the outward limit.

40 A further object of the invention is to produce a novel and easily applied and removed latch with means for causing it to engage the knuckle and prevent its disengagement.

45 A further object of the invention is to provide means whereby the cars are uncoupled in case the draw-bar is released from the car, the parts being arranged so that any separation of the cars beyond a predetermined distance will result in disengaging the latch and 50 shoulder and permitting the cars to uncouple in order that the draw-bar may not be drawn out to fall on the track and wreck a train.

A further object is to produce a coupler in which the engagement of the latch and the shoulder occurs below the pulling-line, thus 55 serving to wedge the rear of the knuckle against the roof of the coupler-head, insuring a firm engagement between the latch and shoulders and giving a downward tendency to the latch when a pull is exerted. 60

With the foregoing and other objects in view the invention consists in the details of construction and in the arrangement and combination of parts to be hereinafter more fully set forth and claimed. 65

In describing the invention in detail reference will be had to the accompanying drawings, forming part of this specification, wherein like characters denote corresponding parts in the several views, and in which— 70

Figure 1 is a plan view of a coupler-head in relation to the car. Fig. 2 is a horizontal sectional view thereof, with the knuckle and latch in plan. Fig. 3 is a sectional view on the line 3 3 of Fig. 2. Fig. 4 is a sectional view on the line 4 4 of Fig. 3. Fig. 5 is a perspective view of the knuckle. Fig. 6 is a perspective view of the latch. Fig. 7 is a view similar to Fig. 2, with a modified means of supporting the latch and connecting the latch and knuckle. Fig. 8 is a view in elevation looking at the end of the latch and knuckle. Fig. 9 is a plan view, partly in section, showing the modified connection between the latch and knuckle. 85

In the drawings, A denotes the draw-bar, and B the draw-head. The draw-head has a shoulder C on its lower inner wall, which terminates under the guide D, said guide D extending around the inner rear wall of the 90 draw-head and forming a support for the latch.

A web E is provided in the point of the horn of the draw-head on the same plane as the guide D, and there is a small space between the guide and web for the accommodation of the chain F, which operates through the aperture G of the draw-head. A knuckle H is secured in the draw-head by the pin I, and the knuckle is provided with a shank J, which is preferably provided with a fillet *j* in order 100 to give strength to the same. The rear end of the knuckle is provided with a lug *a*, which engages a similar lug *b* on the wall of the coupler when the knuckle is in operative po-

sition; but the lug of the knuckle swings clear of the lug of the draw-head when the knuckle moves on its pivot. The rear end of the knuckle is also provided with a flange 5 c , which is engaged by the shoulder d of the latch when said latch is engaging the shoulder C , as shown in dotted lines, Fig. 4. The upper edge of the latch is provided with a surface e , designed to be engaged by the retaining-pin f when the latch is thrown up by the operation of the lever g , to which the chain is connected. By this arrangement the latch may be thrown up by an operator, and the operator may leave the car while the latch is set 10 to permit the cars to uncouple. This will be appreciated as a great advantage in practice.

In operation it will be observed that when the latch is elevated it is held elevated by the pin and that disengagement of the pin and 15 the latch takes place when said latch swings in the arc of a circle. When the latch has moved a predetermined distance or until the same is released from the pin, it engages the guide and rides thereover until it passes to the 20 web, where it is supported with the knuckle fully open until set by an operator. This arrangement prevents undue wear on the latch and produces an easy operation, for in the absence of the web the end of the latch 25 would swing over the end of the guide and considerable friction would result from its being drawn up over the end of the guide again.

In the modification shown in Fig. 7 the solid guide is dispensed with and a series of 30 lugs 11 are provided over which the latch may ride. In this modification the connection between the latch and knuckle is also modified in that the latch is provided with a flange 12, and the knuckle has a shouldered extension 35 13, which embraces and engages the flange when the latch is in operative position.

In Figs. 8 and 9 I provide a further modification of the connection means in which the end of the knuckle is socketed, as shown at 40 14, and the latch is provided with a shank 15, having a lug 16, which is designed to pass within the end of the knuckle and turned in order that it may engage the shoulder 17.

A curved rib 18 is provided on the head, as 45 shown in Fig. 7, which is designed to engage a lug 19 on the latch to hold the latch on the knuckle.

The outside of the top of the coupler is provided with two ribs x , extending into a cross-50 rib y , and the cross-rib is formed integral with a single longitudinally-disposed rib z . This arrangement is to receive the bumper on the car and to compensate for the added length to the draw-head to make them the same distance apart as the other coupler which does not have the knuckle of increased length. The said knuckle is made long to increase the leverage and reduce the wear on the latch and its shoulder by reducing the strain.

55 The operating-rod is slideable transversely of the car, and the arm to which the chain is connected engages a bracket a^2 , which is at-

tached to the car. The upper end of the bracket a has a double inclined end a^3 , over which the arm of the operating-rod may ride. 70 When the arm is thrust to the right-hand side of the bracket, the chain is held taut and the latch cannot engage the shoulder and lock the coupler; but when it is desired that the latch shall operate the arm is elevated and the rod 75 is thrust to throw the arm on the opposite side of the bracket to loosen the chain and permit the latch to drop.

The knuckle is provided with a lug h' , having a hole h^2 , which registers with a hole h^3 80 in the coupler-head. This permits the use of a pin to hold the knuckle rigid in case the latch or the shank of the coupler breaks or in case both of the lugs of the coupler break off; or, if wanted, the knuckle can be removed 85 and by inserting a pin in the hole h^3 of the head the shank of any kind in common use that will fit in the draw-head may be held in operative position as a makeshift.

Having fully described my invention, what 90 I claim as new, and desire to secure by Letters Patent, is—

1. In a car-coupler, a draw-head having a shoulder on its inner lower wall and a guide and web on its rear inner wall and on the 95 horn of the guide-iron, a knuckle and latch, a chain working through the coupler-head between the guide and web, the said chain being connected to the car and to the latch in order to release the latch on any separation of the 100 cars beyond a predetermined distance, a pin for holding the latch elevated and means whereby the chain may hold the latch elevated substantially as described.

2. In a car-coupler, a draw-head having a 105 shoulder on its inner lower wall and a guide and web on its rear inner wall and on the horn of the guide-iron, a knuckle and latch, a chain working through the coupler-head between the guide and web, the said chain being 110 connected to the car and to the latch in order to release the latch on any separation of the cars beyond a predetermined distance, a pin for holding the latch elevated and means whereby the chain may hold the latch elevated 115 and ribs on the outer surface of the draw-head to receive the bumper for the purpose of strengthening the distance between the head and end of the draw-bar.

3. In a car-coupler, a draw-head, a knuckle pivoted therein, a locking connection between the draw-head and knuckle and a latch for holding the knuckle closed, a shoulder against which the knuckle acts, said latch engaging the shoulder below the pulling-line and acting 125 to force the engaging members of the head and knuckle into closer contact as and for the purpose described.

4. In a car-coupler, a draw-head, a knuckle 130 therein, having a shank provided with a fillet, a latch pivoted on the shank, interlocking connections between the knuckle and latch, a guide-rib engaging a flange on the latch to prevent disengagement of the latch and knuckle,

an operating-rod on the car having a thrust, an arm thereon, a chain from the arm to the latch, a bracket contacting the arm, said chain holding the latch elevated when the arm is to one side of the bracket and releasing the latch when the arm is on the opposite side of the bracket as and for the purpose described.

In testimony whereof I affix my signature, in the presence of two witnesses, this 10th day of September, 1902.

GEORGE C. HARLIN.
